UNITED STATES PATENT OFFICE.

JNO. CUSTER, OF FINLEY, OHIO.

WATER-WHEEL.

Specification of Letters Patent No. 20,335, dated May 25, 1858.

To all whom it may concern:

Be it known that I, JOHN CUSTER, of Finley, in the county of Hancock and State of Ohio, have invented a new and Improved 5 Horizontal Water-Wheel; and I do hereby declare that the following is a full, clear, and exact description of the same, reference being had to the annexed drawings, making a part of this specification, in which—
10 Figure 1, is a vertical central section of my improvement. Fig. 2, is a plan or top view of ditto. Fig. 3, is a detached sectional view of a bucket, taken in the line (x), (x), Fig. 1. Fig. 4, is a detached perspective view of ditto.
15 Similar letters of reference indicate corresponding parts in the several figures.

This invention consists in a novel arrangement of the wheel and chute as hereinafter 20 shown, whereby the wheel is rendered capable of being raised and lowered as circumstances may require and the water properly directed into the buckets at any point or position of the wheel within the range of its 25 adjustment.

The invention also consists in the peculiar construction of the buckets and the wheel generally, as hereinafter described whereby a large percentage of power is obtained and 30 the construction of the wheel rendered simple and economical.

To enable those skilled in the art to fully understand and construct my invention I will proceed to describe it.

35 A, represents a circular cast iron plate which is fitted loosely on a vertical shaft B, said shaft being at its lower part of quadrilateral form so that the wheel and plate will rotate together and the plate be 40 allowed to rise and fall on the shaft. On the lower part of the shaft B, an inverted conical hub or boss (a) is formed, and through the plate A, near the shaft B, four screws (b), pass vertically, the lower ends of said 45 screws resting on the top of the hub or boss (a), see Fig. 1. The shaft B, has its lower end stepped in a cross-tree (c) and the upper end of said shaft has its bearing in a cross piece (d) connected with a suitable framing.
50 The upper surface of the plate A, has radial 55 grooves in it, or, radial flanches may be on the upper surface of the plate to form sockets to receive arms (e). These arms are constructed of wood and they project sufficiently far beyond the edge of the plate A,

so that the buckets C, may be attached to them. The buckets C, are constructed of cast iron of peculiar form and are shown more particularly in Figs. 1, 2 and 3. The buckets are formed each of two parts, one 60 part being so constructed as to receive the percussive force of the water and the other part to receive a force from the gravity of the water as it leaves the buckets. The upper parts (f) of the buckets are formed 65 of a top piece (g), a back (h), a side (i), and a bottom piece (j). The top piece (g) and side (i) project from the back (h) so as to form obtuse angles with it, and the bottom piece (j) does not extend wholly 70 across the bucket, but only about half way, a space (k) being allowed, which space forms the orifice of the lower part (l) of the bucket. The lower parts (l) of the buckets are of scoop form as shown clearly 75 in Figs. 1 and 4, the bottoms of said parts being inclined at an angle of about 45°. The outer edge of the back (h) of each bucket is provided with an eye (m) through which the outer ends of the arms (e) pass, 80 and the front edges of the sides (i) of each bucket is notched or recessed to receive the arm of the bucket immediately before it, see Figs. 3 and 4. Each bucket therefore serves 85 as a bearing or support for the one immediately before it, and each bucket is bolted to its arm as shown at (a'). The plate A, and buckets C, are covered by a plate A', secured in proper position by any proper means.

90 D, represents the sluice through which the water is conducted to the wheel, and E, is a cylindrical case in which the wheel is fitted. The sluice D, is made to communicate with the case E, by means of an adjustable mouth F. This mouth F, is formed of a bottom and top piece (n), (n), the outer ends of which are hinged as shown at (n') to a vertical sliding board G, fitted transversely in the sluice D, and having an opening (o) made through it. This board G may be raised and lowered by means of an arm (p) attached to a rock shaft (q) which has a hand lever (r) connected to it. The inner ends of the bottom and top pieces (n) (n) are connected to a vertical sliding bar (s), the upper end of which is attached to a lever (t) see Figs. 1 and 2. It will be seen that the outer ends of the bottom and top pieces (n) (n) may be elevated and de- 100 105 110

pressed by adjusting the sliding board G, and the inner ends of said pieces (n), (n), may be elevated or depressed by operating the lever (t), the pieces (n) (n) working 5 on the hinges (n') as centers.

The operation is as follows: The wheel may be raised or lowered within its case E, by adjusting the screws (b), the plate A being allowed to rise and fall freely on the 10 shaft B, and the water is directed properly into the buckets C, at whatever height the wheel may be placed by adjusting the mouth F, by moving either or both of the levers (t), (r). The wheel therefore may 15 be adjusted according to the height of the water so that a uniform fall may be obtained. The water first acts against the upper parts (f) of the buckets by impact and in passing down into the lower parts (l) 20 of the buckets and out from them, a force is obtained by the weight or gravity of the water, and owing to the form of the buckets as shown the water is allowed to pass very directly through the buckets so that there 25 is but little power lost by friction, a difficulty hitherto attending buckets constructed for effecting the purpose herein shown a large percentage therefore of the power of the water is obtained. The buckets also by 30 being attached to the plate A, by means of the arms (e) arranged as shown render the construction of the wheel extremely simple

and susceptible of being readily repaired in case of a bucket being broken.

I do not claim broadly so forming the 35 buckets of horizontal water wheels that the percussive force of the water as well as that caused by gravity are obtained, for buckets have been devised and arranged in various ways to accomplish this purpose; 40 but, having thus described my invention,

What I claim as new and desire to secure by Letters Patent, is,

1. Placing the plate A, loosely on the shaft B, and rendering the same adjustable 45 thereon by means of set screws (b), or their equivalents in connection with the adjustable mouth F, in the sluice D, the parts being arranged substantially as herein shown and described for the purpose set forth. 50

2. The buckets C, constructed of the form herein shown and described so that the percussive force of the water is obtained and also the force produced by its weight as it passes from the buckets, and the water at 55 the same time allowed to pass in a very direct and uninterrupted manner through the buckets, so as not to occasion much loss of power by friction.

JOHN CUSTER.
